UNITED STATES PATENT OFFICE

128,466

DESIGN FOR A DRESS

Harry Shacter, Westport, Conn.

Application June 28, 1941, Serial No. 101,767

Term of patent 3½ years

To all whom it may concern:

Be it known that I, Harry Shacter, a citizen of the United States, residing in Westport, in the county of Fairfield and State of Connecticut, have invented a new, original, and ornamental Design for a Dress, of which the following is a specification, reference being had to the accompanying drawing, forming part thereof.

I claim:

The ornamental design for a dress, substantially as shown.

HARRY SHACTER.
